UNITED STATES PATENT OFFICE.

WILLIAM H. OLVER, OF OSHKOSH, WISCONSIN.

IRONING-MACHINE.

1,082,548.

Specification of Letters Patent.

Patented Dec. 30, 1913.

Application filed January 15, 1912. Serial No. 671,321.

To all whom it may concern:

Be it known that I, WILLIAM H. OLVER, a citizen of the United States, residing at Oshkosh, in the county of Winnebago, and State of Wisconsin, have invented a new and useful Ironing-Machine, of which the following is a specification.

My invention relates to improvements in ironing machines patented to me November 10, 1908, No. 902,676, and consists of numerous features that add to the ease in which the mechanism can be installed and operated, and which are shown in the accompanying drawings, in which,—

15 Figure 1 is a side elevation of an ironing table, a tailor's pressing board thereon and a short rail suspended from the ceiling of a room, a trolley frame and wheels upon the rail, and a sad iron suspended from the trolley frame. Fig. 2 is an end elevation of said table, press board, rail, trolley and sad iron. Fig. 3 is a plan of the rail, its suspension rods and brace wires of the same. Fig. 4 is a plan upon a larger scale of an 20 end of the trolley rail, and the trolley thereon. Fig. 5 is a longitudinal section of an end of the trolley rail with the trolley thereon, upon the line a, a , of Fig. 4. Figs. 6 and 6 $\frac{1}{2}$, are end views of two styles of clamps 25 that are used upon small rods of $\frac{1}{16}$ inch diameter, more or less, in several places. Fig. 7 is an edge view of one style of a catch that is used. Fig. 8 is an edge view of a 30 stirrup which is suspended from the trolley frame. Fig. 9 is a side elevation showing a modification in the manner of supporting the trolley rail. Fig. 10 is a plan of a trolley rail supported by two arms, the rail being broken at one end for showing the slotted 35 arm below it, said arms being mounted upon the upper ends of two gas pipe pillars which are supported upon the floor of the room in which the machine is located. Fig. 11 is an end elevation showing Fig. 9 turned one 40 quarter around toward the left. Fig. 12 is an edge view of a catch, for the same purpose as the catch in Fig. 7. Fig. 13 is a plan of one of the bracket arms which is used upon the gas pipe pillars. Fig. 14 is 45 a plan of the under side of a collar having oppositely disposed fingers extending below its under face.

Similar numerals and letters indicate like parts in the several views.

50 1, indicates the floor of a room; 2, a pressing table; 3, a press board thereon; 4, a trol-

ley rail, which in Figs. 1 and 2 is suspended from the ceiling of a room by means of round rods 5, which are screwed into the ceiling 6, and in Figs. 9, 10 and 11, is supported by gas pipe pillars 7 extending upward from the floor. The rail in all of the figures, which is preferably of wood, is provided at each end with an angular piece 8, bent into two right angles, upon the lower 55 arm of which the rail is mounted and secured with bolts 9, the upper arms extending from the rail ends, each being provided with a bore 10 (see Figs. 4 and 5,) of a diameter a little larger than that of the rods 5, so that 60 the rail can easily move lengthwise of the rods. It should be noted that the rail is thus suspended by means of said angular pieces above its center of gravity, and will naturally hang downward under all usual 65 conditions of its use.

In Figs. 1 and 3 the rod 5 at the left is provided with two brace wires 11 and 12, one opposite the other and transversely of the rail, which wires consist in part of a 70 coiled spring 13, and extend from the clamp 16 upon the rod 5 to the screw eye 15, which is screwed into the ceiling. The purpose of said springs is, to allow a sidewise swing to the rail in accordance with the sidewise 75 movement of the sad iron during the pressing operation.

The right hand suspension rod 5, is provided with a clamp 16, from one end of which two brace wires 17 and 18, extend to 80 and connect, one with each of the opposite screw eyes 15, to which the wires 11 and 12 are connected, and from the other end of the clamp 16, a brace wire 19, extends to the right, and is connected with a screw eye 15, 85 which is secured to the ceiling and is in the same vertical plane as the rail. It will be observed that the three brace wires upon the right hand rod 5, are not spaced at equal distances apart, the wires 17 and 18, being 90 near together. This is for the purpose of permitting the rail to swing sidewise in accordance with the sidewise movement of the sad iron in the pressing operation. The springs in the brace wires 11 and 12, permit 95 the left hand end of the rail to swing sidewise in accordance with the pull of the pressman while pressing.

At both ends of the rail in Figs. 1 and 2, the rods 5 should extend below the rail and 100 be provided with clamps 14, between which and the upper arm of the pieces 8, a coiled

spring 20, is mounted, but in Fig. 2, the extension is omitted for showing the stirrup 34. The spring at the left is intended to have a slightly greater resiliency than the one at the right, as denoted by its greater length. They allow the rail a degree of vertical movement which is in proportion to the resiliency of said springs and relieve the press-man of the weight of the sad iron to a limited degree.

Figs. 1 and 9, both show the rail in relation to the press board at the right hand end of the rail depressed by the weight of said iron. Figs. 9, 10 and 11 show a modification in the manner of supporting the rail, it being supported upon pillars instead of being suspended. For this purpose, gas pipes 7, are erected in base flanges 21, which are firmly secured to a suitable base, as for instance the floor. The pillars should extend upward some four feet, more or less, above the table, and be placed about six inches back from the longitudinal center of the width of the press board, and when they extend to the floor, if they do not pass through the table, should be secured to it, as is shown at the right of Fig. 9 and front of Fig. 11, by means of the holder 21. Below their upper ends, bracket arms 22, are adjustably secured upon the pillars by means of set screws 23. At the free ends of the arms, holes 24, are bored for receiving about a $\frac{1}{16}$ inch round spring steel rod 25, which is secured therein with set screw 26. At the upper ends of the pillars, arms 27, are secured with set screws 28. Each arm 27, is provided at its outer end with a slot 29, adapted to permit the rods 25, to swing freely therein transversely of the rail. The rods 25 extend upward, the one at the left nearly or quite sixteen inches above the slotted arm, and the one at the right somewhat less as its supporting pillar is longer than the one at the left, and a coiled spring 30, is mounted around each rod between the slotted arm and the upper arm of the piece 8. These springs like the springs 20, permit a vertical movement of the rail ends and the slotted arms allow a sidewise swing of the rail by reason of the resiliency of the rods 25, in accordance with the sidewise movement of the sad iron in the pressing operation.

The trolley frame consists of a block 31, and two side pieces 32, between which side pieces wheels 33, are arranged for revolution. A stirrup 34, is suspended loosely from the bolt 35, which is screwed into or passes through the side pieces and block 31. From the lower end of the stirrup the sad iron is suspended, and the forward and backward movement thereof has a tendency to throw the stirrup out of a vertical position. For preserving its vertical position, the opposite sides of the stirrup are ex-

tended upward above the trolley frame and bent at an angle at 36, and provided with a slot 37, (see Figs. 4 and 8,) and a spring 38, is secured to the block 31 with bolt 39, and extends upward through the slot, so that any movement which throws the stirrup out of a vertical position will be immediately corrected by the spring.

At a point below the trolley rail a cross wire 40, is secured across the stirrup upon which a coiled spring 41 is hooked and depends, and is connected at its lower end with a rod 42, which extends downward through the lower end of the stirrup. Secured to this rod is a collar 43, which is provided with fingers 44, which are adapted to engage the lower end of the stirrup and prevent the rod, and consequently the sad iron, from turning out of its working position, when it is not being used. The sad iron 45, is provided with a bail piece 46, having a tubular piece 47, pivotally secured to it at 47^a, mid way its ends, the tubular piece being adapted to receive the rod 42 and retain it and consequently the sad iron, in the desired vertical position by means of the thumb screw 48. To the piece 46 two wires 49 and 50, are secured loosely, with screws 51, or otherwise, the wire 49 being curved forwardly as is shown in Figs. 1 and 9, for providing ample space for the hand of the operator, and both wires are provided with hooks 52, for connecting with the sad iron upon the pins 53. By unhooking the wires 49 and 50, from the pins 53, the sad iron can be quickly detached from its suspension device. For holding the sad iron when at its backward movement, catches 54 and 54^a, are used, they each consisting of a piece of band spring steel bent as shown in Figs. 7 and 12, the former secured to an extension of a suspension rod 5 by means of clamp screw 55, and the latter secured to a pillar 7 at the right hand end of the table by its clamp screw 55, the catches being adapted to hold the rod 42 in the depressions 56 of the catches as the sad iron is pulled to its backward limit of movement.

It will be observed that the sad iron is suspended by the wires 49 and 50, from opposite sides and at points a little above its center of gravity, and so it will hang when not in use in a horizontal position, whereby it is, when thus suspended, always in position for immediate use, all of which features are of great value relative to ease of operation and speed in pressing.

Having described my invention, what I claim and desire to secure by Letters Patent, is,—

1. In an ironing machine, the combination of a trolley supporting rail, a thin metallic plate secured upon each end of the rail, and extending, one part from each end thereof above the center of gravity of the rail, a per-

foration through each extending part, and vertically arranged rods one at each end of the rail fitted for easily passing through the perforations for guiding the rail in its 5 vertical movement.

2. An ironing machine comprising a rail supported above a pressing table and having a pair of trolley wheels arranged in a frame tandem for revolution therein and adapted 10 to have suspended from said frame a sad iron for being moved back and forth under said rail and with said trolley frame, and a spring for permitting a transverse movement of a rail end in accordance with the 15 sidewise pull upon the rail in the pressing operation.

3. An ironing machine comprising a rail supported above a pressing table having a press board longitudinally of the table and 20 having a pair of trolley wheels arranged in a frame tandem for revolution therein and adapted to have suspended from said frame a sad iron for being moved back and forth under said rail and with said trolley frame, a support for said rail consisting of a gas pipe 25 pillar, one at each end of the table secured to a suitable base, and extending a suitable distance above the pressing table, an arm extending forward from each pillar and adjustably secured thereto, their free ends being substantially vertically above the longitudinal central line of said press board, a bore in the upper side of the outer end of each arm, a spring rod secured in each of 30 said bores and extending upward therefrom, a second arm secured upon each pillar and extending forward above said first named arms, a loop in the outer end of each of said second named arms and inclosing the rod in 35 its companion arm, a coiled spring mounted above each loop around its inclosed rod and supporting, each one end of said trolley rail, and a clamp upon each rod above the rail 40 ends for limiting the upward movement of the rail ends.

4. An ironing machine comprising a rail supported above a pressing table and having a pair of trolley wheels arranged in a frame tandem for revolution therein and adapted 45 to have suspended from said frame a sad iron for being moved back and forth under said rail and with said trolley frame, a suspension device for the sad iron comprising a stirrup loosely mounted upon a bolt upon 50 opposite sides of said trolley frame its upper ends extending and meeting at a point above said trolley frame, a slot formed in its extreme upper end and a spring secured to the trolley frame and extending upward into 55 said slot, and suitable connecting means between the lower end of the stirrup and the sad iron, said spring acting to return said stirrup to a position at right angles with the

length of the trolley frame when thrown out of said position.

5. An ironing machine comprising a rail supported above a pressing table and having a pair of trolley wheels arranged in a frame tandem for revolution therein and adapted to have suspended from said frame a sad 70 iron for being moved back and forth under said rail and with said trolley frame, a suspension device for the sad iron comprising a stirrup depending from opposite sides of said trolley frame, a connecting wire from 75 one side to the other of the stirrup below the rail, a coiled spring depending from said connecting wire, a rod depending from said spring and passing through the lower end of said stirrup, a collar secured upon said 80 rod and adapted to limit the downward movement of said rod by the engagement of its lower surface with the lower end of said stirrup, fingers on said collar adapted to engage the lower end of the stirrup and hold 85 the collar from turning when at the lowest limit of its movement, and suitable connections between the lower end of said rod and the sad iron.

6. An ironing machine comprising a rail 90 supported above a pressing table and having a pair of trolley wheels arranged in a frame tandem for revolution therein and adapted to have suspended from said frame a sad iron for being moved back and forth under 95 said rail and with said trolley frame, a suspension device for the sad iron comprising a stirrup depending from opposite sides of said trolley frame, a spring connecting the stirrup and a rod that is arranged to pass 100 through the lower end of said stirrup, a tubular piece secured adjustably to the lower end of said rod, a bail piece pivotally secured at its mid length to the lower end of said tubular piece, a wire pivotally connected 105 and extending from each end of said bail piece, and being pivotally connected with opposite long sides of the sad iron at such points relative to its center of gravity that it will be suspended in a substantially 110 horizontal position.

7. In an ironing machine, the combination of a sad iron, a pivotally mounted bail piece suspended above the sad iron transversely thereof, a wire depending from opposite ends of said bail piece and connecting, each wire to one of the opposite long sides of the sad iron, one wire being straight and the other curved outwardly in a direction toward the pointed or forward end of 120 the sad iron for providing space for the hand of the operator.
